UNITED STATES PATENT OFFICE.

ERNST GUSTAV SIEVERT AND HENNING SVENSSON, OF SUNDBYBERG, NEAR STOCKHOLM, SWEDEN.

HIGH-TENSION CABLE TO PREVENT A BREAKING DOWN OF THE INSULATION.

Application filed November 9, 1925, Serial No. 67,949, and in Sweden November 20, 1924.

The present invention refers to an improvement in high-tension cables to prevent a breaking-down of the insulating layer. Such a breaking-down will generally take place in such points of the cable, in which the insulating power of the layer has been reduced, for instance by a somewhat less thickness, already at the manufacture, or has got any other unintentional reduction of the specific electric insulating power of the insulating material. If a puncture has once happened in some point of the insulating layer the cable will be very rapidly destroyed as the puncture is combined with chemical as well as thermal processes which exert influence upon adjacent parts of the insulating material and which will gradually cause a total breaking-down between the very conductor of the cable and the earth.

According to this invention, in order to remove this source of disturbances, one or more layers of an insulating material, having an electric insulating power inferior to the remaining insulating material, are applied into the insulating layers of the cable.

This arrangement effects an equalizing of the tension, by which fact the causes of the initiating of the partial puncture are removed or at least, essentially reduced. It is evident that the equalizing tension will be the better and more complete the lower the electric insulating power of the equalizing layer is. On the other hand a reduction of the specific electric insulating power of said equalizing layers involves another inconvenience or danger depending upon the fact that if the electric insulating power of the layers is made too small, two partial punctures possibly produced, in spite of the equalizing layers, at a distance from one another counting in the longitudinal direction of the cable, may add so that the result will be inferior to that obtained without any equalizing layer or layers. The electric insulating power of the equalizing layers should, on account of this, according to the invention, also be chosen with regard to the probable distance between weakened points, favoring the arising of partial puncture, of the insulating material in a well made cable,

taking as ground, of course, the figures obtained by experience.

Depending on the structure, the tension and the insulating material used in the cable the probable distance may vary between several thousand times the thickness of the insulating material down to only twice this thickness, and with regard to this circumstance the equalizing layers should be dimensioned in proportion to their electric insulating power in such a way that, in a certain cable structure, each particular equalizing layer, counting axially, is able to maintain the maximum potential difference between two breaking-down points located in the equalizing layer, provided these points are not located at a shorter axial distance than the probable minimum distance supposed in advance, which, as already indicated above, is different for different cable structures. As insulating materials for the equalizing layers a plurality of different materials, known per se, may, of course, be used, for instance asbestos, which material has proven to be particularly suitable.

The annexed drawing shows, diagrammatically, an embodiment of a cable according to the present invention, in longitudinal section.

1 is the lead sheath, 2, 3, 4, 5 the several layers of insulating material, 6, 7, 8, 12 the equalizing layers placed between the former and 9 the electric conductor.

If, for instance, the insulating layer 2 at the outside, when manufactured, has got a weakened point 10, the tension will increase at this point, but on the other hand the equalizing layer 6 tends to reduce the tension and equalize it so as to reduce the danger of a breaking down. In the same manner the increasing of tension, due to a possible weak point 11 in the insulating layer 3, is equalized. If, in spite of this, the points 10 and 11 should be punctured, these punctures are, however, prevented from adding by the relatively low electric insulating power of the equalizing layer 6, said equalizing layer preventing (the example chosen being still considered), the voltage drop produced in the point 10 from being trans-

mitted to the point 11, which is supposed to be located at an axial distance from the point 10, at least equal to the probable axial minimum distance, previously indicated, between adjacent weakened points in the insulating layers 2 and 3.

Having now particularly described the nature of our invention and the manner of its operation, what we claim is:

A high-tension cable including an insulating layer, at least one tension equalizing layer arranged into said insulating layer, said tension equalizing layer being formed of asbestos.

In testimony whereof we herewith affix our signatures.

ERNST GUSTAV SIEVERT.

HENNING SVENSSON.
